Primary Examiner — Catherine Tuttle(74) *Attorney, Agent, or Firm* — John T. Dipre; David V. Upite; Leonard W. Lewis**CLAIM**

The ornamental design for a bottle, as shown and described.

DESCRIPTION

FIG. 1 is a perspective view of the bottle embodying our new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines are included for the purpose of illustrating portions of the bottle that form no part of the claimed design.
